UNITED STATES PATENT OFFICE

150,106

DESIGN FOR A DOUBLE SEATED VEHICLE FOR CHILDREN

Joseph L. Baker, Wichita, Kans.

Application December 30, 1946, Serial No. 135,849

Term of patent 3½ years

(Cl. D34—15)

To all whom it may concern:

Be it known that I, Joseph L. Baker, a citizen of the United States, residing at Wichita, in the county of Sedgwick and State of Kansas, have invented a new, original, and ornamental Design for a Double Seated Vehicle for Children, of which the following is a specification, reference being had to the accompanying drawing, forming a part thereof.

Fig. 1 is a perspective view of a double seated vehicle for children, showing my new design.

Fig. 2 is a top plan view thereof.

I claim:

The ornamental design for a double seated vehicle for children, as shown.

JOSEPH L. BAKER.
